DOOR CONTROLLING MECHANISM AND
LIMIT SWITCH

Boley A. Andrews, Kansas City, Mo., and George M. Pro, Kansas City, Kans., assignors, by mesne assignments, to The Vendo Company, Kansas City, Mo., a corporation of Missouri

Application March 24, 1947, Serial No. 736,684

4 Claims. (Cl. 200—47)

1

This invention relates to a system for remotely controlling the operation of movable structure and more particularly to a control unit for garage doors or the like.

The primary object of this invention is to provide mechanism for operating a garage door or the like in response to a suitable control unit, having a carrier mounted within a pair of spaced apart tracks suspended from a garage ceiling, which carrier has an electric motor secured thereto for driving an elongated screw interposed between the said tracks and movable longitudinally with respect to the tracks to shift the garage door to and from a horizontal position underlying said tracks.

A still further object of this invention is to provide a door controlling mechanism having a carrier mounted for limited movement within a pair of spaced apart tracks suspended from a garage ceiling for reciprocating an elongated door actuating screw, which carrier is provided with an electric motor energized upon closing of a three pole double throw switch, and a plurality of springs operable to automatically open said switch either when the door reaches a closed or an open position or upon stalling or partial stalling during movement to or from a closed position.

Many additional objects of this invention will be made clear or become apparent during the course of the following specification, reference being had to the accompanying drawings, wherein:

Fig. 1 is a fragmentary sectional view of a garage or the like showing the door operating mechanism mounted therein and operably attached to the garage door.

Fig. 2 is a fragmentary cross-sectional view taken on line II—II of Fig. 1 on an enlarged scale.

Fig. 3 is a fragmentary top plan view of the garage door actuating mechanism per se.

Fig. 4 is a fragmentary cross sectional view taken on line IV—IV of Fig. 3.

Fig. 5 is a cross sectional view taken on line V—V of Fig. 3 and looking in the direction of the arrows.

Fig. 6 is a detailed cross sectional view taken on line VI—VI of Fig. 1 looking in the direction of the arrows.

Fig. 7 is an enlarged detailed cross sectional view taken on line VII—VII of Fig. 2.

Fig. 8 is a substantially central, longitudinal cross sectional view taken through the carrier body and rotatable sleeve mounted therein.

It is contemplated that the mechanism hereof

2

be used with a door such as that shown in Figs. 1 and 2 and designated by the numeral 16. This door 16 consists of a number of hingedly interconnected sections of conventional character, and travels within suitable overhead and vertical tracks 17 mounted within a garage or other building 18.

The operating mechanism per se is broadly designated by the numeral 20 and includes a pair 10 of opposed, substantially parallel, channel-like tracks 22 of identical character. These tracks 22 are disposed with the interior of their channels in facing relation and mounted on a ceiling 24 of garage 18 through the medium of a number 15 of brackets 26 depending from ceiling 24.

One end wall 28 of garage 18 has an opening 30 therein, closable by door 16 and one end of each of the tracks 22 is secured as at 32 to this wall 28.

20 A carrier broadly designated by the numeral 34 is disposed between the tracks 22 and mounted for limited reciprocation therein through the medium of a pair of rollers 36, one in each of the tracks 22. This carrier 34 includes a main body 25 or casting 38 receiving stub pins 40 for rotatably mounting the rollers 36. A bracket 42 mounted on body 38 extends downwardly as illustrated in Fig. 5 to support an electric motor 44 on one face thereof and a switch box 46 on its opposite face.

30 Body 38 has a continuous bore 48 formed therein and disposed substantially midway between tracks 22 and having its axis parallel with the tracks 22. A sleeve 50, freely rotatable within the bore 48 of body 38, extends beyond bore 48 at each end thereof to receive a pulley 53 and a collar 54. This pulley 52 and the collar 54 are each securely keyed to the sleeve 50 as is clear in Fig. 8.

35 The sleeve 50 is internally threaded to receive an elongated screw 52 that is extended beyond each end of sleeve 50 in substantially coextensive relationship to tracks 22. One end of this screw 40 52 adjacent wall 28 has a head 54 threaded thereon, and this head 54 is bifurcated outwardly from screw 52 as shown in Fig. 7 to receive an enlarged end 56 of a rod 58.

45 Aligned openings are formed in the bifurcated legs of head 54 and the end 56 of rod 58 to receive a shaft 60. Rod 58 is free to swing on the shaft 60 and shaft 60 carries a pair of rollers 62 on the free ends thereof, disposed in the tracks 22 as shown in Fig. 2. A bolt 64 passes through the head 54 and shaft 52 to hold the latter against rotation.

55 A bracket 66 bolted to the inner face of door

16 near its top, has an opening near its uppermost free end to receive a hook 68 on the free end of rod 58. Any suitable spring-loaded latch means may be provided in rod 58 to releasably hold hook 68 engaged with the bracket 66.

Tracks 22 each carry a link 70 at the ends thereof opposite to wall 28 of building 18 for receiving a bar 72 bridged between links 70. A block 74 of rubber or other material, which will have no damaging effect on the threads of screw 52, is mounted on bar 72 in underlying supporting relationship to the screw 52.

A pair of arms 76 adjacent the rollers 36 extend rearwardly from body 38 toward the end of tracks 22 having block 74 thereon to mount a cross member 78 interposed between tracks 22. A member 78 midway between tracks 22 to receive one end of a leaf spring 82. Spring 82 extends toward block 74 and passes through a slot 83 formed in one leg of an L-shaped cross bar 84. This cross bar 84 is secured to tracks 22 by a pair of U-shaped clamps 86, and an extension 88 on bar 84 projects upwardly to slidably receive an elongated rod 90.

Leaf spring 82 carries a washer and pin assembly 92 at the free end thereof and a spring 94 is coiled about spring 82 between washer 92 and cross bar 84. A second coil spring 96 is mounted on spring 82 between cross bar 84 and link 80.

Rod 90 carries a collar 98 on one end thereof and a coil spring 100 is loosely mounted on this rod 90 between collar 98 and extension 88. A second coil spring 101 on rod 90 is disposed between the extension 88 and a collar 102 adjustably secured to rod 90 intermediate its ends.

A pair of spaced apart upstanding walls 103 integral with body 38 have aligned openings therein for slidably receiving a sleeve 105. This sleeve 105 is longer than the distance between walls 103 and carries a transverse pin 106 in one end thereof. The opposite end of sleeve 105 loosely telescopes one end of rod 90 adjacent collar 102 and joins with rod 90 by a second pin 107. A pair of spaced apart collars 108 are attached to sleeve 105 between walls 103.

A three pole double throw switch 109 mounted in box 46 has an actuating arm 110 extending upwardly through aligned slots in box 46 and body 38. The free end of this arm 110 is disposed between the collars 108 on sleeve 105.

Motor 44 has a pulley 111 on the outermost end of its drive shaft, and an endless belt 112 interconnects pulleys 53 and 111.

An electronic relay control unit 113 has suitable electric wire connection 114 with the motor circuit (not shown) of motor 44 through box 46, and is preferably mounted upon ceiling 24 of garage 18 adjacent to carrier unit 34.

A microphone 115 mounted on the outer face of wall 32 above opening 38 has suitable conductors 116 extending into control unit 113 as shown in Fig. 1. This microphone 115 consists essentially of a Rochelle salt crystal which is normally resonant at a narrow range of supersonic frequencies and a special type of diaphragm construction which will extend the response of the crystal over a wide range of frequencies.

Rochelle salt crystals as produced commercially are resonant to a narrow range of frequencies and therefore, the response to sound waves are greatest when vibrating in this narrow range of frequencies. For utilizing this type of crystal in microphones for voice frequencies, the crystal is cemented to a highly damped circular dia-

phragm which is clamped at the outside edges in order to insure true speech reproduction hence resulting in good quality sound pick-up.

Inasmuch as the highly damped diaphragm is clamped at the outside edges, the response begins to fall off at high sound frequencies and becomes inefficient if not entirely inoperative at frequencies exceeding 10,000 cycles per second. To pick up frequencies exceeding 10,000 C. P. S. the crystal itself can be used without a diaphragm, however, its resonant characteristics are such that it can be used only for a narrow band of frequencies. As an example, a 20,000 C. P. S. crystal will give excellent response for a band of frequencies at 20,000 C. P. S. This band generally is 300 C. P. S. wide.

In order to extend the response characteristics of this narrow band crystal, this crystal is cemented to a special type of diaphragm. This diaphragm consists of a piece of metal foil about .002 inches thick and curved in a semi-circle. The center ends of the diaphragm are cemented to supports and the crystal is cemented to the outside center of the semi-circle. This type of mounting will allow the ends of the diaphragm to vibrate with a greater degree of freedom and thus pick up supersonic frequencies which will actuate the crystal.

The circuit for supplying electrical energy to the motor 44 is of conventional character having connection to a suitable source, not shown. In addition to the switch 109, this motor circuit should have one or more auxiliary switches for permitting an operator to close the circuit independently of switch 109, as well as an impulse switch 212, shown in Fig. 15 and operable by the relay control unit as hereinafter more fully set forth. A relay having mechanical interlocking contact points, is also provided in this motor circuit, all conventionally connected to the end that the circuit will always be closed through switch 109 whenever anyone of the auxiliary switches is actuated.

It is clear from the foregoing that the direction of rotation of the pulley wheel 53 determines whether door 16 is raised or lowered to a position covering opening 30. If, while motor 44 is operating in one direction, one of the auxiliary switches on the impulse switch 212 is actuated to close the relay, the motor circuit will be broken. If the relay coil circuit is again closed, the motor circuit will again be energized until switch 109 is actuated. Each actuation of switch 109 in either direction reverses motor 44 and at the same time closing the motor circuit.

Rotation of pulley 53 in either direction and thereby sleeve 50 causes screw 52 to travel longitudinally through sleeve 50 toward or from the wall 28 respectively. When screw 52 moves away from wall 28 to pull door 16 to the open position, the door load will move carrier 34 and leaf spring 82 carried thereby a limited distance toward wall 28, compressing the spring 94 against the cross bar 84. Such movement of carrier 34 will move rod 90 in the same direction. If the door load becomes greater due to stalling or partial stalling of door 16, the spring 94 will be further compressed until carrier 34 moves to a position causing collar 98 to engage spring 100. When spring 100 engages extension 88, movement of rod 90 ceases and carrier 34 moves switch 109 to a position where arm 110 thereof is actuated to open the circuit for motor 44. As set forth above, if at this point, switch 212 or any one of the auxiliary switches is actuated, the motor will be reversed. Thus, two successive movements of one

of the switches must be performed in order to continue movement of door 16 in the same direction after stalling.

When door 16 reaches the fully open position, it strikes a bumper 117 on tracks 22, causing the same action in spring 94 and rod 99 as aforesaid to operate switch 109 and open the motor circuit.

When door 16 is to be closed, stalling of door 16 or upon reaching a closed position, causes actuation of switch 109 through spring 96, rod 90 and spring 101 in the opposite manner.

It is notable that the entire door actuating assembly is constructed to obviate the necessity of true alignment of any of its parts in order to attain proper operation. Leaf spring 82 and rod 90 are freely slideable in cross bar 84 and extension 88 respectively. Sleeve 105 and rod 99 need not remain in perfect alignment because of the connection 107, and screw 52 rides freely on the block 74.

Having thus described the invention, what is claimed as new and desired to be secured by Letters Patent is:

1. In actuating mechanism, an elongated screw mounted for non-rotating reciprocation on its longitudinal axis and adapted for connection at one end thereof with apparatus to be actuated; an element screw-threaded on the screw for rotation thereon and mounted for reciprocation longitudinally thereof; a pair of devices for yieldably holding said element against reciprocation in either of two directions respectively; a pair of spaced electrical contacts mounted for reciprocation with said element; an electrical conductor arm carried by said element for reciprocation with the element and limited reciprocation relative thereto between said electrical contacts; and means limiting the extent of reciprocable movement of said arm with the element whereby upon predetermined reciprocation of said element against either of said devices the arm is moved against a corresponding electrical contact.

2. In actuating mechanism, an elongated screw mounted for non-rotating reciprocation on its longitudinal axis and adapted for connection at one end thereof with apparatus to be actuated; an element screw-threaded on the screw for rotation thereon and mounted for reciprocation longitudinally thereof; a pair of devices for yieldably holding said element against reciprocation in either of two directions respectively; a pair of spaced electrical contacts mounted for reciprocation with said element; an electrical conductor arm carried by said element for reciprocation with the element and limited reciprocation relative thereto between said electrical contacts; and means including a pair of opposed yieldable members for limiting the extent of reciprocable movement of said arm with the element whereby upon predetermined reciprocation of said element against either of said devices the arm is moved against a corresponding electrical contact.

3. In actuating mechanism, a reciprocable carrier; a pair of opposed springs operably con-

nected with said carrier for yieldably holding the carrier against reciprocation in either of two directions respectively; a rotatable element mounted on the carrier for reciprocation therewith; an elongated screw mounted for non-rotating reciprocation on its longitudinal axis parallel with the path of travel of the carrier, said screw being in screw-threaded engagement with said element and adapted at one end thereof for connection with apparatus to be actuated; a pair of spaced electric contacts on said carrier; an electrical conductor arm mounted for limited reciprocation on the carrier in parallelism with said axis of the screw and between the contacts; and a pair of opposed springs operably connected with said conductor arm for yieldably holding the latter against reciprocation with the carrier in either of two directions respectively.

4. In actuating mechanism, a reciprocable carriage; an elongated flat spring extending from the carrier in parallelism with the path of travel thereof; stationary structure slidably receiving the spring; a spring coiled about the flat spring on opposite sides respectively of said structure for yieldably holding the carrier against reciprocation in either of two directions respectively; a rotatable element mounted on the carrier for reciprocation therewith; an elongated screw mounted for non-rotating reciprocation on its longitudinal axis parallel with the path of travel of the carrier, said screw being in screw-threaded engagement with said element and adapted at one end thereof for connection with apparatus to be actuated; a pair of spaced electric contacts on said carrier; an electrical conductor arm mounted for limited reciprocation on the carrier in parallelism with said axis of the screw and between the contacts; and a pair of opposed springs operably connected with said conductor arm for yieldably holding the latter against reciprocation with the carrier in either of two directions respectively.
